ALVIN WYCKOFF, OF LOS ANGELES, CALIFORNIA, ASSIGNOR TO FAMOUS PLAYERS-LASKY CORPORATION, OF NEW YORK, N. Y., A CORPORATION OF NEW YORK.

COLORING MACHINE.

Application filed October 30, 1919. Serial No. 334,623.

The present invention relates to improvements in machines for tinting or coloring films and particularly to machines in which coloring matter is transferred between films by pressure contact. It is an object of the invention to provide a machine of this character which will handle film and particularly motion picture film accurately and efficiently.

10 The present invention is directed particularly to provide improvements in machines of the character set forth in U. S. Patent No. 1,303,837, issued to Wyckoff and Handschieg, on May 13, 1919, or machines adapted to carry out the process set forth in that patent or in Patent No. 1,303,836, issued to Wyckoff and Handschieg, on May 13, 1919. In machines of this general character the films have heretofore been moved by the 20 member (preferably the drum or the like) on which they are carried when in pressure contact, or they are pulled over or around the member (the drum) on which they are carried in pressure contact. In either case, 25 before the films are brought into pressure contact on the drum they are pulled through or over a mechanism, designed to keep a tension on them. The means, by which the films have heretofore been kept tight, or by 30 which they have been kept under tension before coming in contact with each other, have embodied various arrangements of rollers provided with friction or brake means. It has been found in practice that 35 such arrangements for keeping tension on the film are not satisfactory in that the films do not keep in accurate register, do not feel evenly and oftentimes kink. In the machine provided by the present invention the films are kept tight by driven 40 rollers which are so provided with resilient friction or brake means as to compensate for shrinking or difference in lengths of films and at the same time keep even tension on the films being fed into pressure 45 contact.

There are other objects and features of the invention which will be best understood from the following detailed description of 50 a preferred embodiment of the invention throughout which reference is had to the accompanying drawings, in which—

Fig. 1 is a front elevation of the machine;

Fig. 2 is a side elevation of the machine, being a view taken as indicated by line 55 2—2 on Fig. 1; Fig. 3 is a plan view of the machine; Fig. 4 is a detail section taken by line 4—4 on Fig. 2; Fig. 5 is an enlarged detail section taken as indicated by line 5—5 on Fig. 3; Fig. 6 is a detail section 60 taken as indicated by line 6—6 on Fig. 2; Fig. 7 is a detailed section taken as indicated by line 7—7 on Fig. 2; Fig. 8 is an enlarged section taken as indicated by line 8—8 on Fig. 1; and Fig. 9 is a view of a 65 portion of the machine taken as indicated by line 9—9 on Fig. 2.

Throughout the drawings numeral 10 designates the main frame of the machine comprising uprights 11 and 12 which extend 70 upwardly from a common base 13 and are connected near their upper ends by cross member 14. The main frame 10 is preferably cast and its various parts are preferably integral.

75 A horizontal shaft 15 is carried in bearings 16 and 17 in the upright frame members 11 and 12, respectively. The shaft 15 extends beyond the upright 11 and has mounted on its extending portion a film carrying drum 20. The film carrying drum 20 is the member on which the films 21 and 22 are brought into pressure contact. The drum 20 comprises a rim 29 supported from hub 28 by spokes 27. At the edges of face 80 23 of drum 20 there are sprocket teeth 24 which are spaced and proportioned to engage the perforations 25 in standard motion picture films. The engagement of the film 85 perforations 25 by the teeth 24 prevents slipping or moving of the films after they have been brought into engagement with the drum 20 and with each other. In order to facilitate checking up or examining the 90 films, when they are in pressure contact, to 95 see if they are in proper register, transparent panels 26, preferably glass, are provided in the rim 29 between the spokes 27. The panels 26 can be mounted or carried 100 in the rim 29 in any suitable manner; for instance, as shown in the drawings, they may be beveled and set in conical openings and a beading 30, which fits a groove 31, may be provided behind them. The drum 20 is kept spaced the proper distance from 105 the upright 11 by the inner edge of hub

28 engaging arm 32 carried by shaft 15 between the drum 20 and the upright member 11. The drum 20 is prevented from moving away from the upright member 11 by hub 34, of worm wheel 35, engaging the inner end of the bearing 16, as clearly shown in Fig. 2.

The drum 20 is driven in the direction indicated by the arrow in Fig. 1, by worm gear 36 meshing with worm wheel 35 which is tight on shaft 15. The worm 36 is mounted on and driven by a shaft 37 carried in suitable bearings 38. The shaft 37 has mounted on it a gear 40 driven by a gear 41 mounted on the main shaft 39 carried in bearings 41^a as shown in Fig. 6. The ends of the shaft 39 are provided with suitable flanges 42 by which the machine may be connected with other machines or mechanisms or by which the machine may be connected to a driving mechanism such as a motor, engine, or the like.

A clutch mechanism 43 is provided between the main drive shaft 39 and the shaft 37 so that the machine can be thrown out of operation without stopping or disconnecting the main drive shaft 39. The clutch mechanism 43 comprises a slider 45 which has clutch jaws 46 and which is splined or slidably keyed by means of key 47 to the shaft 39. The spur gear 41 is free on the shaft 39 and is provided with a hub 48 in which are cut clutch jaws 49 adapted to co-operate with clutch jaws 46. It will be readily understood how the jaws 46 and 49 are moved in or out of engagement by moving member 45 toward or away from the gear 41, and that the gear 41 is only driven when the jaws 46 and 49 are in engagement. Any suitable mechanism may be arranged for shifting or moving the member 45, for instance, a rod 50 may be slidably carried in the frame 10 so as to be parallel with the shaft 39 as shown in Fig. 6. The rod 50 may be moved manually or by a lever arrangement and a sleeve 51, having a finger 52, may be mounted on the rod 50 so that the finger 52 engages an annular groove 53 in the slider 45 and thereby causes movement of the slider 45 when the rod 50 is moved.

The driving arrangement just described makes it possible to connect several machines or units and drive them synchronously and at the same time be able to disconnect or stop any particular machine without interfering with the other machines.

The color carrying negative film or the film which carries the materials to be transferred to the uncolored or positive film is carried on a spool 60 and is fed to the drum 20 so that its color carrying face is out. The spool 60 and the mechanism through which the film 22 passes or runs before it engages the drum 20 is carried by a U-shaped frame 61 which is carried between the uprights 11

and 12 by a rod 62. The frame 61 comprises a base portion 63, which is slidably mounted on the rod 62, and has a long arm 64 extending upward from the end of the base 63, which arm is adjacent to the upright 11, and has a short arm 65 extending upward from the end of the base 63, which arm is adjacent to the upright 12. The short arm 65 is connected with the upright 12 by an adjusting mechanism 66 which will be hereinafter described. The spool 60 is revolvably mounted at the top end of the arm 64 and is mounted on the side of the arm 64 which will cause it to be in line with the drum 20. The color carrying film 22 upon leaving the spool 60 passes around a friction or drag sprocket or roller 67 mounted on projection 68 which extends from the arm 64, as clearly shown in Fig. 1. The spindle 69 which carries the roller 67 extends from the projection 68 and has, screw threaded on its outer end, a knurled nut 70. A shoulder 70^a on the spindle 69 spaces the roller 67 from the arm and allows the spindle to be locked firmly on the arm by nut 70^b. A resilient washer 71, preferably rubber, is carried on the spindle 69 between the outer end of the roller 67 and the inner end of the knurled nut 70. The knurled nut 70 is screwed onto the spindle 69 until the roller 67 is pressed or held against the shoulder 70^a with sufficient pressure to cause the desired amount of friction or drag. The friction on the roller 67 is preferably just sufficient to make it necessary to draw or pull the film around it and is sufficient to prevent it from being rotated or carried around by inertia. The film is prevented from slipping on the roller 67 by sprocket teeth 74, similar to teeth 24 on the drum 20, and the film is guided onto the roller 67 by an idler roller 75. The roller 75 is carried on a shaft 76 which is adjustably carried in a slot 77 and is locked in the desired position by a nut 78. The roller 75 presses the film against the roller 67 and the teeth 74 which extend from the roller prevent the film from being pulled or dragged around the roller without rotating it.

The film 22 after passing around the roller 67, as shown in Fig. 1, engages and passes around a drum or roller 80. The roller 80 is a driven member and is the member from which the film is fed onto the drum 20. The roller 80 is mounted on and driven by a shaft 81 which is carried in a suitable bearing 82 in arm 64. The roller 80 is not mounted tightly on shaft 81 but is adjustably connected to the shaft through worm gear 83 and worm 85. The worm wheel 83 is firmly mounted on the shaft 81 so as to mesh with the worm 85 which is carried on a shaft 86 supported by a bracket 87 which is firmly mounted on the hub of roller 80 as shown in Fig. 8. It will be readily understood how this construction makes it possi-

ble to rotatively adjust the roller 80 relative to the shaft 81 by rotating the worm 85.

The shaft 81 is driven through a friction mechanism from a gear 90 mounted on shaft 91. The gear 90 engages and drives a gear 92 which is freely mounted on shaft 81. A cylindrical casing 93 extends from the gear 92 and has screw threaded in its outer end a cap 94. A helical spring 95 extends 10 between a shoulder 96, formed in the cap 94, and a ring 96^a which is tightly keyed onto the shaft 81. The ring 96^a has a recess 97 into which the spring 95 extends and a friction washer 98, preferably leather, is interposed between the spring and the ring, as clearly shown in Fig. 5. It will be readily understood how the shaft 81 is driven from gear 92 through the spring and ring, and that the pull or drag exerted on the film by 20 the roller 80, is dependent upon the adjustment or pressure put upon the spring 95. This particular connection not only provides a friction joint or connection which may slip on application of sufficient pull on the 25 roller 80 but also provides a resilient connection (due to the spring 95) which prevents sudden slipping or jerking of the various parts and which acts as a shock absorbing element. By varying the pressure on 30 spring 95 the tension maintained on the film can be very accurately regulated and when the spring is properly adjusted the machine will operate continuously without attention.

The shaft 91 which is carried in and extends between the uprights 11 and 12 is driven from vertical shaft 99 through bevel gears 91^a and 99^a. The vertical shaft 99 is carried in a suitable bearing 100 formed in the cross member 14 of the frame 10 and is 40 driven from horizontal shaft 15 through the bevel gears 101 and 102. The gear ratios throughout the entire mechanism hereinabove described, are preferably such as to cause the drum 20 to have a peripheral speed slightly faster than that of the roller 80. This difference in speed together with the resilient friction drive provided by the mechanism hereinabove described will cause the film 22 to be kept under an even tension 45 between the drum 20 and the roller 80 and prevents kinking or accumulation of film between the roller 80 and the drum 20. Such a difference in peripheral speed of drum 20 and roller 80 together with the adjustment of spring 95 will be preferably 55 such as to cause the roller 80 to drag or pull the film 22 from the spool 60 around the roller 67 at the same time causing sufficient pull to come upon the film between roller 80 and drum 20 to cause a continual slippage in the drive mechanism of roller 80.

The positive film 21, or the film that is to be brought into pressure contact on the drum 20 with the color carrying film 22, 65 is received by the machine either from an-

other machine, or similar mechanism, or from a reel. The film 21 upon entering the machine runs over an idler pulley 110 which is mounted at the upper end of arm 111 of frame 112. The frame 112, except for the 70 difference in shape between arm 64 and arm 111, is the same as the frame 61 and is mounted in the main frame 10 in exactly the same manner as is frame 61. From the idler pulley 110 the film 21 runs over a second 75 idler pulley 113 which feeds it onto a drag or friction roller 114. The roller 114 is the same as roller 67 hereinbefore described and it co-operates with the idler 113 in substantially the same manner as the roller 67 co-80 operates with the roller 75. The film 21 upon passing around the roller 114 engages and passes around a drum or roller 115 which in construction, in manner of driving and in operation, is the same as the roller 80 85 hereinbefore described. The roller 115 is mounted on a shaft 116 which is the same as shaft 81 and the shaft 116 is driven from gear 90 by its engagement with a gear 117. Gear 117 is connected by friction means with the shaft 116 in the same manner as the gear 92 is connected with the shaft 81. The roller 115 performs the same function and has the same action on film 21 as the roller 80 has 90 on the film 22, that is, it drags or pulls the film into the machine around the drag pulley 114 and feeds it to the drum 20 so that it is always under uniform tension.

From the roller 115 the film 21 with its face inward is brought into contact with the face of film 22 on drum 20; and due to the two films being under tension as they are fed onto the drum 20 they are pressed together on the face of the drum. The bringing together of the films causes transfer of color from the negative 22 to the positive 21. It will be understood that this invention is not limited in any way to the manner in which the negative film 22 is colored or to any chemical treatment given to the films prior to or after passing through the machine. The machine, however, is particularly adapted to handle films that have been chemically or otherwise treated, as it will efficiently handle films that have been stretched or shrunk. The amount of tension on the outer or positive film governs the contact pressure between the two films; the difference in tensions on the two films (which difference is regulated by the proper adjustment of the two yielding driving means of rollers 80 and 115) causes differential stretching of the two films, which may thus be brought to registering lengths as set out in the patents before referred to. The amount of color transferred from negative 22 to positive 21 is dependent upon, among other things, the pressure with which the films are held together and the time that they are in contact. It will be understood 110 115 120 125 130

that the color to be transferred and the portion of the positive to be colored do not enter into or concern this invention but are dependent upon the color carried by negative 22 and the location of the color on the negative.

In order to assure perfect contact between the two films and to prevent slight kinking or separation of the films while they are on the drum 20 a rubber roller 120 is mounted on an arm 121 so as to engage the outer face of the outer film 21 just after it is brought into contact with the film 22. The arm 121 is mounted on a shaft 170 carried by the frame 10 so that roller 120 is kept against the films by a spring 122 connected to an arm 171 which is also mounted on the shaft 170 as shown in Fig. 9. The spring 122 is adjustable by being attached to a plate 175 which is adjustably attached to the frame 10 at 176. The pressure with which the roller 120 engages film 21 can be regulated by adjusting plate 175. The action of this roller is to squeeze the films together into uniform contact, squeezing out all air between them. The roller 120 can be lifted away from the films by handle 123 which extends from the arm 121, as shown in Fig. 1, and it can be lifted so as to stay in the up position by lifting it until the arm 171 is in the position shown in dotted lines in Fig. 9.

Upon being carried around the drum 20, due to the rotation of the drum, the films are kept in constant even pressure contact until they separate and leave the drum 20. Upon leaving the drum 20 the films 21 and 22 run over and leave the machine over rollers 125 and 126, respectively. The rollers 125 and 126 are mounted on arm 32 and are driven by spring belt 128 so as to have a peripheral speed a little greater than that of the drum 20. The rollers 125 and 126 being driven in this manner cause a constant pull or tension to be kept upon the films 21 and 22 while they are in engagement on the drum 20 and due to their being driven by a spring belt they are not positively driven but may be slipped relative to the belt sufficient to keep them at the proper speed. The rollers 125 and 126 are of the same construction and mounting, each being mounted on a spindle 129 and each having a pulley 130 formed at its inner end. The spring belt 128 which runs over the pulleys 130 runs over and is driven by a pulley 131 which is pivotally mounted on a spindle 132 extending from the arm 32. The pulley 131 is driven from a gear 133 mounted on the hub of the drum 20 so as to engage and drive gear 134 which is mounted on the hub 135^a of pulley 131.

The time during which the films 21 and 22 are kept in pressure contact on the drum may be varied by varying the position at which they are taken off of the drum 20 over the rollers 125 and 126. The varying of the positions of the rollers 125 and 126 around the

drum 20, relative to the point at which the two films 21 and 22 engage the drum 20, can be done by varying the position of the arm 32 which is freely carried on shaft 15. It will be readily understood how lowering the arm 32 from the position shown in Fig. 1 will cause the period of time, during which the films 21 and 22 are in pressure contact, to be decreased while if the arm 32 is raised from the position shown in Fig. 1 the period of time during which the films are kept in pressure contact will be increased. The arm 32 is held in the desired position by a catch 135 which is pivotally connected to frame 10 at 136. The catch 135 has an extended portion 135^b which forms a handle and has teeth 133 cut in it to engage teeth 132 which are cut in the arm 32 as shown in Fig. 7. The catch 135 is arranged so that it is held in engagement with the arm 32 by gravity which makes it unnecessary to employ a spring or other holding means. The arm 32 can be moved or adjusted by lifting handle 135 so as to move teeth 133 out of engagement with teeth 132.

The mechanism so far described in detail has been designed for handling the films 21 and 22 without kinking and so that they will be brought into pressure contact in continuous perfect register. In order to assure proper transverse alignment of rollers 80 and 115 and their respective co-operating pulleys and rollers with the drum 20 so that the films will be fed accurately onto the drum 20, regulating or adjusting mechanism 66 are provided in connection with the frames 61 and 112. The frames 61 and 112 being slidably carried on the rods 62 and 112^a, respectively, may be moved laterally on the rods 61 and 112^a so that the sprockets 80 and 115, etc., are brought into proper lateral alignment with the drum 20. There is an independent adjusting mechanism 66 for each frame which comprises a screw 150 carried at the upper end of upright member 12 so that it is screw threaded into the arm 65 of the frame. The screw 150 although free to rotate in the upright 12 is prevented from lateral movement by a shoulder 151 and a cap 152, as clearly shown in Fig. 2. It will be readily understood how rotation of the screw 150 will cause lateral movement of the frame 60 or 112 as the case may be, due to the screw 150 being screw threadedly engaged in the arm 65.

Having described a preferred embodiment of my invention I do not wish to limit myself to the particular details hereinabove set forth but wish to reserve to myself any changes or modifications that may appear to those skilled in the art and which fall within the scope of the following claims. And one thing to which I may further call attention is this: that this invention is not limited to coloring motion picture films, although for

convenience and definiteness of description I have so described it.

Having described a preferred form of my invention, I claim:

5. 1. In a machine of the character described, a revolving drum adapted to carry a film, and yielding means for placing the film under tension as it is fed to the drum, said means comprising a roller over which the film passes, drive means for the drum and roller, and a yielding connection between the drive means and the roller. 70
10. 2. In a machine of the character described, a revolving drum adapted to carry superimposed films, and yielding means for placing the films fed to the drum under tension, said means comprising a plurality of revolving rollers, actuating means for revolving the drum and rollers, and a resilient slip connection between the actuating means and each of the rollers. 75
15. 3. In a machine of the character described, a supporting frame, a revolving drum to carry superimposed perforated films mounted on the frame, the drum being toothed on its periphery for engaging the perforations of the films, actuating means for revolving the drum, a plurality of revolving rollers adjustably supported on the frame, 80
20. the rollers being toothed on their peripheries for engaging the perforations of the films, actuating means for revolving the rollers, said means tending to rotate the rollers at a slower peripheral speed than that of the drum, and a slip connection between the roller actuating means and rollers to allow the roller to be rotated by the film at the same peripheral speed as the drum. 85
25. 4. In a machine of the character described, a supporting frame, a revolving drum to carry superimposed perforated films mounted on the frame, the drum being toothed on its periphery for engaging the perforations of the films, actuating means for revolving the drum, a plurality of revolving rollers adjustably supported on the frame, 90
30. the rollers being toothed on their peripheries for engaging the perforations of the films, actuating means for revolving the rollers, said means tending to rotate the rollers at a slower peripheral speed than that of the drum, and a slip connection between the roller actuating means and rollers to allow the roller to be rotated by the film at the same peripheral speed as the drum. 95
35. 5. In a machine of the character described, a supporting frame, a revolving drum to carry superimposed perforated films mounted on the frame, the drum being toothed on its periphery for engaging the perforations of the films, actuating means for revolving the drum, a plurality of revolving rollers adjustably relative to their driving means adjustably supported on the frame, the rollers being toothed on their peripheries for engaging the perforations of the films, 100
40. actuating means in connection with the drum, actuating means for revolving the rollers, said means tending to rotate the rollers at a slower peripheral speed than that of the drum, and a resilient slip connection between the roller actuating means and rollers to allow the rollers to be rotated by the films at the same peripheral speed as the drum. 105
45. 6. In a machine of the character described, a supporting frame, a revolving drum to carry superimposed perforated films mounted on the frame, the drum being toothed on its periphery for engaging the perforations of the films, actuating means for revolving the drum, a plurality of revolving rollers laterally and rotatively adjustably supported on the frame, the rollers being toothed on their peripheries for engaging 110
50. the perforations of the films, actuating means for revolving the rollers, said means tending to rotate the rollers at a slower peripheral speed than that of the drum, and a resilient slip connection between the roller actuating means and rollers, to allow the rollers to be rotated by the films at the same peripheral speed as the drum. 115
55. 7. In a machine of the character described, a frame, a revolving film carrying drum thereon, a plurality of revolving rollers over which film passes on its way to the drum, a common driving means for the drum and rollers causing the rollers to move at a slower peripheral speed than the drum, and a resilient and frictional slip element in the driving means adjacent the rollers. 120
60. 8. In a machine of the character described, a frame, a revolving film carrying drum thereon, a plurality of revolving film feeding rollers over which film passes on its way to the drum, a common driving means for the drum and rollers causing the rollers to move at a slower peripheral speed than the drum, and resilient and frictional slip elements in the driving means adjacent the rollers, said elements embodying two engaging frictional plates one in driving connection with the rollers, and a spring drivingly connected to and pressing against the other plate, said second mentioned plate being driven solely through the spring. 125
65. 9. In a machine of the character described, a drum, a plurality of feed rollers over which film passes on its way to the drum, means for driving the drum and rollers, said means including yielding means for retarding the speed of rotation of the rollers. 130
70. 10. In a machine of the character described, a drum, a plurality of feed rollers over which film passes on its way to the drum, means for driving the drum and rollers, said means including adjustable yielding means for retarding the speed of rotation of the rollers. 135

11. In a machine of the character described, a drum adapted to carry superimposed films, a plurality of rollers over which the film is fed to the drum, drive means for the drum and rollers, said means including resilient means for adjustably retarding the speed of rotation of the rollers. 70
12. In a machine of the character described, a toothed drum adapted to carry superimposed films, a plurality of toothed rollers over which the films are fed to the drum, means for positively driving the drum and rollers, said means including yielding means for adjustably retarding the speed of rotation of the rollers relative to the drum. 75
13. In a machine of the character described, a toothed drum adapted to carry superimposed films, a plurality of rollers over which the films are fed to the drum, means for positively driving the drum and rollers, said means including yielding means for exerting a tension on the films between said rollers and drum. 80
14. In a machine of the character described, a film carrying drum for carrying superimposed films adapted to rotate at a constant speed, yielding means for independently feeding the films to the drum under tension, said means comprising a plurality of rollers, drive means for the rollers, and a resilient slip connection between the rollers and the drive means. 85
15. In a machine of the character described, a drum adapted to carry superimposed films, a plurality of rollers over which the films are fed to the drum separately, means for positively driving the drum, drive means for the rollers, said means including an adjustable yielding connection whereby the films, through the medium of the drum, rotates the rollers, ahead of their driving means and against the action of said yielding connection. 90
16. In a machine of the character described, a member adapted to carry superimposed films, a plurality of rollers over which the films are fed to the drum, drive means for the rollers, said means including an adjustable connection whereby the rollers may be forcibly rotated ahead of their driving means. 95
17. In a machine of the character described, a drum for carrying superimposed films, a plurality of rollers over which the films are fed to the drum, means for driving the drum and rollers, said means including an adjustable resilient connection whereby the rollers may be rotated ahead of their driving means. 100
18. In a machine of the character described, a drum adapted to carry superimposed films, teeth on the periphery of the drum for engaging the perforations of the films, a plurality of toothed rollers over which the films are fed to the drum, means for driving the drum and rollers, said means including adjustable yielding means whereby the rollers may be rotated ahead of their driving means by the pull of the films upon the drum. 105
19. In a machine of the character described, a revoluble toothed drum adapted to carry superimposed films, drive means for the drum, a plurality of toothed feed rollers, shafts on which the rollers over which the films are fed to the drum are revolubly mounted, means for driving said shafts, said means including an adjustable yielding connection whereby the shafts may be rotated ahead of their driving means, and an adjustable driving connection between the rollers and their shafts whereby the rollers may be rotatively adjusted relative to the shafts. 110
20. In a machine of the class described, a frame, a drive shaft revolubly mounted on the frame, a film carrying drum rigidly mounted on the shaft, a member slidably mounted on the frame to move parallel to the axis of the drum shaft, a shaft revolubly mounted on said slideable member with its axis parallel to the axis of the drum shaft, a film feed roller mounted on the second mentioned shaft, drive means for the drum shaft, a gear on the drum shaft, a gear on the feed roller shaft, a shaft having a gear connection with the gear on the drum shaft and a gear connection with the gear on the feed roller shaft whereby the latter may be moved by the slideable member without interrupting its driving connection. 115
21. In a machine of the class described, a film carrying drum, a feed roller over which the film passes onto the drum, a common drive means to positively drive the drum and roller, and means in connection with the roller to rotate it relative to the driving means. 120
22. In a machine of the class described, a drum for carrying superimposed films, a plurality of feed rollers, a common driving means for said drum and rollers, and means for rotatably adjusting said feed rollers relative to the drum. 125
23. In a machine of the character described, a drum for carrying superimposed films, a plurality of film feed rollers, means for positively driving said drum and feed rollers at uniform speed, means to positively rotatably adjust said rollers relative to their driving means, and a resilient slip connection in connection with the roller driving means, whereby the rollers may be independently rotated at different speeds relative to the drum. 130
- In witness that I claim the foregoing I have hereunto subscribed my name this 14th day of October, 1919. 135
- ALVIN WYCKOFF.
